UNITED STATES PATENT OFFICE

PERCY BUTCHER, OF JACKSONVILLE, FLORIDA

PISTON

Application filed February 21, 1928. Serial No. 255,874.

This invention relates to pistons of the type shown in my Patent #1,478,887, granted December 25, 1923.

An object of the invention is to provide a piston body having an expanding shell with means in the form of a wedge ring that is interposed between the body and shell for maintaining the parts of the piston in sealing or fluid-tight engagement.

Another object is to provide a piston composed of a body and a sectional shell with means in the form of expansible coil springs for pressing the adjacent surfaces of the piston parts together so as to prevent leakage therebetween.

Another object is to produce an efficient, strong and durable piston which may be economically constructed and operated.

Other objects and advantages will herein-after appear.

The views of the drawings are:

Figure 1 is an elevation, partially in vertical longitudinal section of a piston constructed according to the preferred embodiment of my invention;

Fig. 2 is a vertical longitudinal section of the piston body shown in elevation in Fig. 1;

Fig. 3 is a perspective of the ring which is interposed between the piston body and the surrounding shell;

Fig. 4 is a perspective of the piston, parts being in section;

Fig. 5 is a detail vertical longitudinal section, illustrating a modified form of my invention;

Fig. 6 is a vertical longitudinal section through a piston valve showing the application of my invention thereto;

Fig. 7 is a perspective of one of the shell sections shown in Fig. 6;

Fig. 8 is a perspective of one of the piston bodies shown in Fig. 6; and

Fig. 9 is a vertical longitudinal section of another piston valve illustrating a further form of the invention.

Referring to the drawings, and especially to Figs. 1 to 4 inclusive, the piston comprises a cylindrical body 1 having a series of beveled faces 2, 3 and 4 formed on its exterior. The faces provide a plurality of bearing surfaces,

the purpose of which will be hereinafter apparent. The arrangement of the faces 2 and 3 should be such as to provide an annular rib 5 near the top of the body 1.

The lower portion of the body 1 is reduced in diameter a distance substantially equal to the depth of the rib 5, so as to provide an annular horizontal shoulder 6.

The body 1 is hollow and it has inwardly projecting bosses 7 for the reception of a wrist pin (not shown).

Surrounding the sides of the body 1 is a shell composed of a plurality of sections 8 (in the present instance two).

The shell sections define a cylindrical structure so that the piston will fit snugly in a cylinder.

The interior of the shell sections are formed with beveled portions 9, 10, 11, 12 and 13.

The surfaces 9 and 10 provide an annular groove having beveled surfaces that coact with the surfaces 2 and 3 of the body 1.

The opposed edges of the shell sections are preferably formed with alternate notches 14 and projections 15 so that they fit one into the other to provide labyrinthine joints extending longitudinally of the piston.

When the shell sections are assembled on the body 1 there is an annular space below the shoulder 6, the bottom of this space being closed by the beveled surface 12.

A plurality of recesses 16 are formed in the shoulder 6 of the body 1 (in the present instance three).

The recesses 16 have an irregular configuration so as to receive bosses 17 of a ring 18 and an expansible spring 19.

One portion of the recesses 16 is rectangular, having a vertical wall 20 and a horizontal wall 21.

The remainder of the recesses include an upwardly inclined surface 22 that terminates above the wall 21 in a relatively short horizontal surface 23.

The surface 23 is connected to the wall 21 by a vertical surface 24.

A notch is thus formed in the upper wall of the recesses 16 for a purpose to be herein-after more fully described.

One face of the ring 18 is beveled, as indicated at 25. This surface of the ring bears against the surface 12 of the shell sections, and in this way the ring will be supported by the shell.

The bosses 17 are adapted to fit within the portion of the recesses 16 defined by the surfaces 22, 23 and 24. Therefore, the bosses have correspondingly formed surfaces 26, 27 and 28 for respectively coacting with the surfaces 22, 23 and 24.

The springs 19 are mounted in the portion of each of the recesses 16 defined by the vertical wall 20 and horizontal wall 21. One end of the spring abuts the wall 20, while its opposite end abuts the vertical face 28 of the bosses 17.

The springs 19 tend to move the ring 18 partly around the body in a rotating manner. 20 This action will provide a fluid tight engagement of the beveled surfaces of the body 1 and the corresponding surfaces of the shell sections 8, the ring 18 functioning as means for wedging the parts together, regardless of 25 piston speed or inertia which might cause movement of the shell sections if the ring was not employed. Furthermore, the inclined surfaces 26 of the bosses will cause equal movement of the ring downwards of 30 the piston body thereby positively sealing the coacting surfaces. This action of the wedge ring is limited to the outward movement of the shell sections to the limit of their expansion within the walls of the cylinder.

35 A slightly modified application of the invention is shown by Fig. 5, wherein the bosses on the ring 18 are eliminated, and vertically disposed springs substituted therefor.

Referring to Fig. 5 the shoulder 6 of the 40 body 1 is formed with vertical recesses 31 in which are disposed expandable coil springs 32 (only a single recess and spring being shown). The springs bear against the upper horizontal 45 face of the ring 18 and thus force the beveled face of the ring into contact with the surface 12 of the shell sections. In other respects the construction is similar to that heretofore described.

Obviously it is immaterial just what type 50 of prime mover or engine utilizes the above described features of my invention, since pistons or plungers constructed as above described may be employed advantageously in steam engines of the double or single acting 55 type, as well as in uniflow engines, pumps, etc.

Moreover, without departing from my invention, I may use the construction described in connection with piston valves, in either of the ways suggested in Figs. 6 to 9, inclusive.

60 Referring now to Figs. 6 to 8, inclusive, the piston valve is designed for use in a chest or casing in which fluid under pressure is admitted to the central portion of the valve. The piston includes a body 35 and cylindri-

65 The heads are formed with annular ribs 37 having beveled sides 38, 39 and 40 for coaction with the parts of a correspondingly formed sectional expanding shell 41.

70 The sides 39 of the ribs are formed with a plurality of recesses 42 in which are inserted expandable coil springs 43. These springs function in the same manner as the springs previously described, but it will be noticed that such springs are disposed perpendicular to the coacting beveled faces of the body, 75 and shell sections.

76 In order to prevent the shell sections from rotating around the heads 36, a pin 44 carried by the shell sections, is passed through 80 an opening 45 formed in the heads 36.

85 A cotter pin 46 is passed through the extremity of the pin 44 lying within the heads 36 to retain the shell sections and springs in position when the piston passes the valve, 90 and to prevent disassembly of the parts when the piston is not mounted in its chamber.

95 It is understood, of course, that the opposed edges of the shell sections are formed with alternate notches 47 and projections 48 so that they fit one into the other to provide labyrinthine joints, as previously described.

100 In the form of the invention shown in Fig. 9, the head 50 of a piston valve is formed with annular ribs 51 and 52.

105 The rib 51 has a beveled side 53, while the rib 52 has a beveled side 54, such beveled surfaces being opposed to each other to form a groove 55.

110 The side of the rib 52 opposite to the side 54 provides a vertical shoulder 56.

115 A sectional expanding shell 57 encircles the head 50. This shell has an annular rib 58 with beveled sides for coacting with the sides of the groove 55 of the head 50.

120 Near one end of the shell there is a beveled surface 59 which is, when the shell is assembled on to the head, disposed at a distance from the shoulder 56, thereby providing an annular space for a wedge ring 60.

125 The ring 60 has a beveled surface 61 for coacting with the surface 59 of the shell sections.

130 The ring 60 is provided with a plurality of recesses 62 (only one being shown). Similar recesses 63 are formed in the shoulder of the head 50.

135 When the shell sections are assembled on the head, the recesses 62 and 63 are aligned so as to receive expandable coil springs 64. The purpose of the springs 64 is to force the beveled face of the ring 60 against the correspondingly formed surface of the shell sections so as to seal the joints between the coacting surfaces of the piston valve body in 140 the manner heretofore described.

145 With the above described arrangement of parts leakage past the piston or piston valve in either direction will be effectually prevented, as well as leakage between the body 130

and the shell sections or through the joints between the adjacent edges of the shell sections, and the true center line of the body is maintained with the true center line of the cylinder bore, regardless of wear of the shell sections or difference in expansion between the shell sections and the body. Furthermore, the wedge ring will prevent side slap of the body, as will be readily understood.

10 The invention claimed is:—

1. The combination in a piston, of a body having a plurality of beveled surfaces thereon, an expanding shell mounted on the said body, said shell being composed of a plurality of independent segmental sections and including inclined surfaces coacting with the beveled surfaces of the body, the bottom of the shell extending beyond the bottom of the said body and being provided with an inwardly projecting rib having an upper beveled surface disposed in spaced relation to the bottom of the said body, and a ring interposed between the said rib and the bottom of the said body, said ring having surfaces correspondingly formed to the adjacent surfaces of the said body and the said shell sections.

2. The combination in a piston, of a body having a plurality of beveled surfaces thereon, an expanding shell mounted on the said body, said shell being composed of a plurality of independent segmental sections and including inclined surfaces coacting with the beveled surfaces of the body, the bottom of the shell extending beyond the bottom of the said body and being provided with an inwardly projecting rib having an upper beveled surface disposed in spaced relation to the bottom of the said body, a plurality of recesses formed in the bottom of the body, and a ring interposed between the said rib and the bottom of the said body and having bosses projecting into the said recesses, said ring having surfaces correspondingly formed to the adjacent surfaces of the said body and the said shell sections.

3. The combination in a piston, of a body having a plurality of beveled surfaces thereon, an expanding shell mounted on the said body, said shell being composed of a plurality of independent segmental sections and including inclined surfaces coacting with the beveled surfaces of the body, the bottom of the shell extending beyond the bottom of the said body and being provided with an inwardly projecting rib having an upper beveled surface disposed in spaced relation to the bottom of the said body, a plurality of recesses formed in the bottom of the body, said recesses having an inclined surface and an angular surface, a ring interposed between the said rib and the bottom of the said body, bosses projecting upwardly from the ring and having inclined surfaces for coacting with the inclined surfaces of the said recesses, said ring having surfaces correspondingly formed

to the adjacent surfaces of the said body and the said shell sections, and expansible coil springs mounted in the portions of the recesses having the said angular surfaces for the purpose of exerting tension against the ends of the said bosses.

4. The combination in a piston of a body having exterior beveled bearing surfaces, a shell composed of a plurality of segmental sections formed to cooperate with the bearing surfaces of the said body, and substantially enclosing it, a shoulder formed in the body near one end thereof, a beveled rib formed on the shell and disposed in spaced relation to the said shoulder, a ring interposed in the space between the said rib and the said shoulder, said ring having a beveled surface bearing against the adjacent surface of the said rib, and tension means between the said ring and the said shoulder.

5. The combination with a piston body, of a sectional shell movable into an expanded position, said shell having a beveled portion, a circularly movable wedging member carried by said body provided with a beveled portion adapted to coact with the beveled portion of said shell, and resilient means whereby a rotary movement of said wedging member may be accompanied with an axial movement, so that said shell may be moved into an expanded position.
